SHIELDED WIRE COVERING

Harry E. Thompson, Providence, R. I., assignor to
 Anaconda Wire & Cable Company, New York,
 N. Y., a corporation of Delaware

Application June 2, 1934, Serial No. 728,804

3 Claims. (Cl. 173—266)

This invention relates to improvements in electric conductors and particularly to the provision of a shielded covering adapted to substantially envelop a conductor.

5 The invention will be fully apparent from the following detailed disclosure when read in connection with the accompanying drawing and will be defined with particularity in the appended claims.

10 In the drawing—

Fig. 1 is a view partly in section and partly in elevation of an electric conductor having a covering applied thereto embodying the invention; Fig. 2 is a view partly in section and partly 15 in elevation of a shielded tubing adapted to enclose an insulated conductor.

A characteristic feature of the invention relates to the provision of a jacket including interwoven strands of fibrous and metallic elements 20 enveloped with a coating carrying metallic particles adapted to conductively coat with the metallic strands in order to form an effective shielding envelope around the conductor. I deem it important to combine the metallic shielding 25 strands of the sheath or coating surrounding the conductor with a layer of metallic shielding particles in order to secure an effective shield to cut down corona losses or to otherwise shield the enclosed conductor against electro-static 30 disturbances.

The combined action of the coating of metallic particles and the metallic strands gives rise to more effective shielding than the presence of either the metallic particles alone or the metallic 35 strands alone would give. It is believed that this superiority arises because the finely divided metallic particles used alone as a coating have a relatively low conductivity. And while the wires alone have a relatively high conductivity the 40 interstices between adjacent wires provide gaps which I believe would cause current leakage due to the existence of corona. The metallic particles closing such gaps therefore conductively contact with the metallic strands with the result that 45 an effective shielding envelope having a high overall conductivity about the conductor is secured, thus materially eliminating corona losses.

The wire or conducting strands of the covering 50 may constitute either part or all of the filling strands of a woven jacket whose warp strands are formed of cotton or other fibrous material. The presence of interwoven cotton strands with the wire is desirable because it lends flexibility to the covering and also provides a foundation

to which the binder carrying the conductive metallic particles may readily adhere.

Referring to the accompanying drawing which exemplifies the invention, the cable, wire, or other conductor, is indicated at 10. This may be 5 covered with any usual or suitable type of insulation indicated conventionally at 12. Over the insulation, there is secured a jacket indicated generally at 14 embodying the present invention. This jacket includes a multiplicity of 10 longitudinally extending cotton or other fibrous warp strands 16, which are interwoven with helical metallic filling strands 18. These strands are preferably of flexible wire, such as copper or the like of good conductivity. This wire may also 15 be in the form of a flap strip or ribbon-like element.

I regard it important that the metallic helical member shall give a minimum of approximately 20 seventy percent coverage in order to form an effective shield. It is also desirable to form a conducting path between the adjacent convolutions of the metallic filling strands in order to negative the inductive characteristics which are 25 inherently present in the helical current-carrying conductors. For this purpose, the outer layer of metallic particles indicated at 20 is provided and in some cases I also consider it important to include one or more warp strands 16 which will be formed of copper or other 30 conducting material, such metallic warp strands can also be utilized for grounding the shielding cover. The powdery-like component of the shield may be carried in a suitable binder, such as cellulosic lacquer. Such lacquer is deemed advantageous 35 because it resists attack by oil, water, gasoline, or the like. It also has a high degree of flexibility. Thus the conductors embodying my invention are well suited for use as ignition cables or in other environments, where they are exposed to the normally deteriorating action of lubricating oil, gasoline, or the like. The binder, such as lacquer, can be adhesively bonded to the fibrous cotton strands, and thus the powdery metallic component of the shield can be effectively 40 and inseparably secured to the jacket formed of the interconnected metallic and fibrous strands.

Instead of securing the shield directly to the insulation of the covering, it is also contemplated that such shield may be furnished in the form of 50 a tubing adapted to receive electric conductors, in which case the tubing of my invention will serve to shield the conductors housed therein. Fig. 2 illustrates such tubing wherein the fibrous warp strands are indicated at 16, the metallic 55

shielding strands at 18' and the powdery coating carried by the lacquer or other binder is indicated at 20'.

The fibrous strands of the shielding jacket 14 5 may be impregnated with waterproofing or preserving material, such as asphalt, stearin pitch, or the like, or such strands may be rubberized by a latex treatment, such as known in the art.

While I have described quite precisely the specific details of the embodiment of the invention illustrated it is to be understood that various modifications and substitution of equivalents may be made by those skilled in the art without departure from the invention as defined in the 15 appended claims.

What I claim is:

1. In combination, an electric conductor, a shielded covering therefor comprising a jacket of interconnected copper and fibrous strands in 20 which the copper strands constitute approximately seventy percent of the superficial area of the jacket and a layer of metallic particles conductively coating with the copper strands to form a shielding envelope about the core, said metallic particles being interspersed throughout a 25 binder characterized by flexibility and resistance to the destructive effect of water, oil and gasoline.

2. In combination with an electric conductor, a shielded covering therefor comprising a tubular structure made up of longitudinally extend-

ing fibrous warp strands and at least one longitudinally extending metallic warp strand, said warp strands being interwoven with the convolutions of a helical metallic filling strand and a layer of metallic particles interspersed throughout a body of cellulosic lacquer forming a flexible binder resistant to the deteriorating effects of oil, water and gasoline, the said metallic strands constituting not less than seventy percent of the superficial area of the tubing so that 10 in coaction with said metallic particles the combined structure is effective to negative the inductive characteristics which are inherently present in said helical metallic strands.

3. In combination with an electrical conductor, 15 a covering therefor comprising a tubular structure made up of longitudinally extending fibrous warp strands, said warp strands being interwoven with the convolutions of a flat ribbon-like 20 helical metallic filling strand and a layer of metallic particles interspersed throughout a body of a flexible binder resistant to the deteriorating effects of oil, water and gasoline, the said metallic strands constituting at least seventy percent 25 of the superficial area of the shielded covering so as to negative the effect of currents which are normally set up by induction in such helical strands.

HARRY E. THOMPSON. 30
